UNITED STATES PATENT OFFICE.

JOHN NAPOLEON ANGELL, OF FORT PIERRE, SOUTH DAKOTA.

COMBINED STEAM-GAGE AND SAFETY-VALVE.

1,044,001.

Specification of Letters Patent.

Patented Nov. 12, 1912.

Application filed December 19, 1911. Serial No. 666,762.

To all whom it may concern:

Be it known that I, JOHN NAPOLEON ANGELL, a citizen of the United States, residing at Fort Pierre, in the county of Stanley and 5 State of South Dakota, have invented new and useful Improvements in Combined Steam-Gages and Safety-Valves, of which the following is a specification.

The general object of the invention is to 10 simplify the construction of safety valves and steam gages, and to this end the invention consists in a combined safety valve and steam gage in which the indicator hand and outlet to the atmosphere are controlled by a 15 single element, the latter in turn being operated directly by the steam.

Other objects will appear and be better understood from the following description taken in connection with the accompanying 20 drawings, in which,

Figure 1 is a view of the device partly in side elevation and vertical section and also showing a sectional detail of a boiler and the device connected thereto. Fig. 2 is a 25 detail horizontal section on the line 2—2 of Fig. 1. Fig. 3 is a view similar to Fig. 2 but on the line 3—3 of Fig. 1.

5 indicates the upper portion of a boiler to which there is connected an apertured 30 plate 6 and through these parts there is screwed one end portion of a pipe 7 through which the steam passes into the hollow cylinder 8 which is connected to the other end of the pipe 7.

35 The steam entering the cylinder 8 presses on a piston or plunger 9 and moves the latter against the action of a spring 10 which is connected to the piston. The spring is adjusted, or in other words, its tension may 40 be varied by turning the screw 12 which extends through a stuffing box 13 in the lower end of the cylinder 8 and has a skeleton portion 14 through which the steam from the pipe 7 passes and which is connected by a 45 swivel 15 to the spring 10. In the present instance the head 14 is shown as screw threaded and engaging with the threaded portion 16 in the cylinder so that when the screw 12 is turned, the distance between the 50 head and piston 9 will be varied.

17 indicates an arcuate dial which is suitably secured to the upper end of the cylinder 8 and has bearings for the arbor 18 upon which is mounted the indicator hand 19 and 55 a crank 20, which latter is connected to the

piston 9 by means of the connecting rod 21 which extends through a stuffing box 22 in the upper end of the cylinder. Thus, when the steam forces the piston upwardly the free end of the indicator hand will be moved 60 to that division on the dial which represents the number of pounds pressure in the boiler.

The outlet tube 23 is arranged so that when the piston moves upwardly sufficiently far to move the indicator hand to the division 65 on the dial which represents the maximum steam pressure required in the boiler, communication between the atmosphere and other portion of the cylinder now below the piston will be established, whereby, the 70 steam from the boiler will pass directly into the atmosphere until the pressure is reduced sufficiently to admit of the piston descending below the outlet 23.

The brace 24 which connects with the couplings 25 and 26 on the boiler and cylinder respectively, coöperates with the pipe 7 to form a rigid support for the cylinder.

Although I have shown and described one embodiment of the invention it is to be understood that I am not to be limited to the specific arrangement and construction of parts since various changes may be made, within the scope of the appended claims without departing from the spirit or sacrificing any of the advantages of the invention.

What I claim as new is:

1. A combined steam gage and safety valve comprising a cylinder adapted for 90 connection to a steam boiler and having an outlet opening, a piston in the cylinder and arranged to control the passage through said outlet opening, a gage including an indicator hand connected to said piston, a 95 spring connected to the piston, and means for varying the tension of the spring.

2. In a device of the class described, the combination of a cylinder, a piston arranged in the cylinder, a spring connected to the 100 piston, and means for varying the tension of the spring and including a skeleton head screwed into the cylinder and connected to the spring.

In testimony whereof I affix my signature 105 in presence of two witnesses.

JOHN NAPOLEON ANGELL.
